UNITED STATES PATENT OFFICE.

GABRIELE ACOCELLA, OF MONTREAL, QUEBEC, CANADA.

SURGICAL INSTRUMENT.

Application filed March 3, 1922. Serial No. 540,877.

To all whom it may concern:

Be it known that I, GABRIELE ACOCELLA, a subject of the King of Great Britain, and residing at the city of Montreal, in the Province of Quebec, in the Dominion of Canada, have invented a new and useful Surgical Instrument, of which the following is the specification.

The invention relates to a surgical instrument as described in the present specification and illustrated in the accompanying drawings that form part of the same.

The invention consists essentially of the novel features of construction pointed out broadly and specifically in the claims for novelty following a description in detail of the preferred form of the invention.

The objects of the invention are to furnish to the medical profession an instrument for the inspection of certain organs of the human body as well as for the treatment of the parts; to facilitate the practice of physicians and insure accuracy in the treatment of hidden diseases; and generally to provide an efficient means of inspecting and treating the urethra, cystolithic and other organs, such as uterus and pleura.

In the drawings, Figure 1 is a perspective view of the instrument.

Figure 2 is an inverted plan of the superior part.

Figure 3 is a plan view of the inferior part.

Figure 4 is an end view of the instrument.

Figure 5 is a cross sectional view on the line 5—5 in Figure 1.

Figure 6 is a cross sectional view on the line 6—6 in Figure 1.

Figure 7 is a longitudinal sectional view on the line 7—7 in Figure 4.

Figure 8 is a perspective detail of a directing plate.

Like numerals of reference indicate corresponding parts in the various figures.

Referring to the drawings, the superior part 1 terminates in the solid reflector head 2 having the guiding rounded offset tip 3 to aid in the insertion in the passage and organ. The other end of the part 1 carries one half 4 of a disc end and this half has a serrated edge 8 at the split and the wire rod holes, 9 and 10.

The telescope 11 in a plurality of sections is mounted in the disc half 4 and the inner section 12 is longitudinally fluted to fit into a grooved orifice in the disc half 13 at the

end of the inferior part 14 said disc half 13 having the serrated edge 15 matching the serrated edge 8.

The disc half 13 supports the glass tubes 16 and 17 and is formed with a boss 18 near the outer end, which projects outwardly to the extent of the solid end 2 beyond the groove 19 in said end into which the inferior part 14 slides, when the instrument is closed.

The superior part 1 and inferior part 14 are formed to slide in a tongue and groove joint 20 made in the interior so that the exterior is perfectly smooth and without obstruction.

The directing plate 21 is a double curved and polished plate held intermediately by the rod 22 and at the end by the rod 23 thereby holding the plate in a way to adjust its angle to direct a catheter or other treating instrument inserted through the tubes 16 and 17.

The lamp 24 in the form of tiny electric bulbs is mounted intermediate of the length of the superior part 1 and the lamp 25 is mounted in the head 2, which is a highly polished reflector, the inner surface of the part 1 also being highly polished for the same purpose.

In the use of the invention the instrument is inserted in the passage to the organ and then the inferior part is pulled back, which opens the superior part and discloses the organs within the scope of the vision of the operator looking into the telescope from the disc end and at the same time the operator may insert a catheter or other instrument through a tube and direct it to the organ to be treated by means of the directing plate operated by the wires. As soon as the work is completed, the inferior part can be closed into the head and the instrument withdrawn, the inferior part being locked in its closed position by the thumb buttons 26 and 27 mounted on the disc half secured to the superior part. The glass tubes are closed when not in use by the wire plugs 28 and 29 which completely fill the area of the tubes. Another opening 30 is shown in the disc half of the inferior tube which is closed by a suitable plug 31, and is intended for the passage of a surgical instrument.

What I claim is:

1. In a surgical instrument, a superior part having a polished interior and a reflector head, electric lamps in said part, an inferior part slidably connected with said

superior part in a tongue and groove inferior joint and adapted to disclose the lamps and reflector surfaces to the extent desired and a spy glass end to said superior part.

2. In a surgical instrument, a superior part having a solid head offset at the tip and an inner polished surface, an inferior part tongue and groove jointed in the inferior to said superior part and fitting into a groove in said head and having a boss accounting for the beaded edge of said head, electric lamps in said head and superior part, a split disc mounted on said parts and 15 a spy glass fixed to the disc half secured to the superior part.

3. In a surgical instrument, a superior part having a polished inner surface and terminating in a polished reflector head, a disc half mounted on the other end of said part, an electric lamp in said head, an electric lamp in said part away from said head, a spy glass having a plurality of sections and secured to said disc half, an inferior 25 part slidably jointed to said superior part,

a disc half mounted on said inferior part and closing the end and instrument tube mounted in said disc half of said inferior part.

4. In a surgical instrument a superior part having a disc half with a serrated edge at the split at one end and a reflector head at the other end, a spy glass in a plurality of sections extending from said disc half, a directing plate for auxiliary instruments 35 and wires for supporting and adjusting said plate projecting through said disc half, electric lamps in said superior half, an inferior part slidably jointed to said superior part and fitting into said head, a disc half fitted 40 to said inferior part and having a serrated edge matching the aforesaid serrated edge, glass tubes projecting through the disc half of said inferior part and supported therefrom, and thumb buttons locking said disc 45 halves and parts to their closed positions.

Signed at Montreal, Canada, this 24th day of February, 1922.

GABRIELE ACOCELLA, M. D.
